Telephone and Telegraph Company, New York, N. Y.,
a corporation of New York

Application January 10, 1958, Serial No. 49,189

Term of patent 14 years

(Cl. D80—5)

Fig. 3.

Fig. 4.

Fig. 1 is a perspective view showing the front and one end of a display carrying unit for color telephone sets, embodying my new design;

Fig. 2 is a perspective view showing the rear and left end thereof;

Fig. 3 is a left end elevational view of Fig. 1 on an enlarged scale; and

Fig. 4 is a right end elevational view of Fig. 1 on an enlarged scale.

The dominant features of my design reside in the full line portions of the drawing.

I claim:

The ornamental design for a display carrying unit for color telephone sets, as shown and described.
